PHILEMON RISLEY, OF GUNNERSBURY, ENGLAND, ASSIGNOR TO REMINGTON TYPE-WRITER COMPANY, OF ILION, NEW YORK, A CORPORATION OF NEW YORK.

TYPE-WRITING MACHINE.

1,181,545.

Specification of Letters Patent. Patented May 2, 1916.

Application filed June 30, 1915. Serial No. 37,176.

To all whom it may concern:

Be it known that I, PHILEMON RISLEY, subject of the King of Great Britain and Ireland, and resident of Gunnersbury, in the county of Middlesex, England, have invented certain new and useful Improvements in Type-Writing Machines, of which the following is a specification.

My invention relates to typewriting machines and more particularly to means for guiding and feeding cards or stencil sheets in substantially a flat condition in a cylindrical platen machine.

One object of the invention, generally stated, is to provide simple and efficient means of the character specified.

A further object of my invention is to provide means, such as those referred to, which are in the nature of attachments that may be readily embodied in typewriting machines now on the market without modifying, or materially modifying, the structural features of said machines as they now exist.

A still further object of my invention is to provide means whereby the machine may be used for cards or stencil sheets, and for handling the same in substantially a flat condition, or may be readily employed as a typewriting machine adapted for ordinary use and in which the work sheets are bent around the platen and thus fed through the machine.

To the above and other ends which will hereinafter appear, my invention consists in the features of construction, arrangements of parts and combinations of devices set forth in the following description and particularly pointed out in the appended claims.

In the accompanying drawings wherein like reference characters indicate corresponding parts in the various views. Figure 1 is a fragmentary fore and aft vertical sectional view showing the upper portion of one form of typewriting machine embodying my invention, the section being taken on the line $w-w$ of Fig. 3 and looking in the direction of the arrow at said line. Fig. 2 is a detail fragmentary side elevation showing the platen, a portion of the platen frame and some of the associated parts. Fig. 3 is a detail fragmentary plan view of the machine. Fig. 4 is a detail fragmentary front elevation with the parts in section showing the stencil feed and guiding

devices and some of the associated parts, the view illustrating a stencil sheet in position to receive the first line of writing. Fig. 5 is a detail fragmentary perspective view showing one end portion of the detachable supporting bar together with some of the parts carried thereby. Fig. 6 is a detail fragmentary horizontal sectional view taken on the line $y-y$ of Fig. 2 and looking in the direction of the arrow at said line, the parts represented in Fig. 6, however, being the ones at the opposite side of the machine from those represented in Fig. 2. Fig. 7 is a detail fragmentary perspective view showing the latch and some of the associated parts by which the supporting bar is locked in place.

In the drawings I have shown only so much of the typewriting machine as may be necessary to arrive at an understanding of my invention.

In the present instance I have shown my invention embodied in the Nos. 10 or 11 Remington machines in which the invention may be readily incorporated without modifying the structural features of said machines as they now exist. It should be understood, however, that the invention may be embodied in other styles of typewriting machines where found available and may be used for other purposes than those set forth.

Some of the ordinary equipment of the machine is removed such, for example, as the ordinary paper fingers and margin feed rollers, and in lieu thereof I place devices of my invention which enable me to properly position, guide and feed cards or stencil sheets in a flat condition in the machine; although, as shown, these devices may be readily removed when desired and the machine is then in condition for ordinary use.

The frame of the machine comprises corner posts 1 and a top plate 2 over which a carriage is adapted to travel from side to side of the machine under control of the usual letter feed mechanism, not shown. The carriage, as shown in the present instance, comprises end bars 3, a front cross bar 4 and a rear cross bar 5. The front cross bar is grooved for the reception of anti-friction balls or rollers 6 which are likewise received in the oppositely grooved guide face of a fixed rail 7. The rear cross bar 5 is likewise grooved for the reception of anti-friction balls or rollers 8 which are

likewise received in the oppositely grooved face of a fixed guide rail 9, the carriage being thus supported to travel over the top plate in the usual manner. A cylindrical 5 platen 10 is supported by the carriage to receive the impact of the usual upwardly and rearwardly striking type bars against the front face thereof. The platen is supported by a platen frame 11 mounted on 10 parallel links 12 and a roller 13 is carried by the platen frame and co-operates with a shaft rail 14. The usual paper devices including the feed rollers 15 and 16 are employed to co-operate with a work sheet introduced in the rear of the platen in the ordinary manner. The ordinary line spacing mechanism comprising a handle 17, and a line spacing pawl 18 controlled through intermediate actuating devices 19, 20 and 20 21 is employed, the line spacing pawl co-acting with a line spacing wheel 22 secured to the platen at the right-hand end thereof. A spring pressed detent roller 23 co-acts with the line spacing wheel to prevent 25 an accidental displacement of the platen from the position to which it may be turned. A line finder or gage 24 is secured by screws 25 to a member 26 which in turn is secured to the shift rail by screws 27. 30 The usual ribbon vibrator 28 is employed although when stencil writing is to be effected the ribbon is removed. I employ the ordinary initial and final line lock stops 29 and 30, respectively, and the usual initial 35 and final margin stops 31 and 32, respectively, which are carried by the carriage and co-act with the stop 33 carried by the frame of the machine. Finger wheels 34 are secured to the platen shaft 35 to effect 40 a rotative movement of the platen.

The parts thus far described constitute part of the ordinary equipment of the Nos. 10 or 11 Remington machines and further detail description thereof is deemed unnecessary.

In the present instance I make the feed rollers 16 smaller than those ordinarily employed in order to facilitate a feed movement of the card or stencil sheet in substantially a flat condition in front of the feed rollers 16 without said rollers interfering with the feed of the sheet, as will be understood from an inspection of Fig. 1. I also preferably cut away a portion of the top 50 plate, as indicated at 36, and likewise cut away a portion of the type bar segment as indicated at 37.

The attachment whereby I am enabled to handle, feed and guide cards or stencil 60 sheets in substantially a flat condition in the machine, comprises a cross bar 38 which, as shown is rectangular in cross section and is provided at its ends with T-shaped cross heads 39 each of which is provided with a 65 plurality of outwardly projecting support-

ing pins. The pins 40 carried by the cross head at the right-hand end of the supporting bar are received in apertures in which they snugly fit, said apertures being provided in a forwardly extending bracket arm 70 41 which is secured by screws 42 to the right-hand end plate of the platen frame and projects forwardly therefrom. The cross head at the left-hand end of the supporting bar is provided with corresponding bearing or supporting pins 43 which, as will be understood from an inspection of Fig. 7, are received in bearings 44 in a left-hand bracket arm 45 secured by screws 46 to the left-hand end plate of the platen frame. 75 From an inspection of Figs. 2, 3 and 7 it will be understood that a sliding latch, designated as a whole by the reference numeral 47, is normally held in the locking position, indicated in Fig. 2, by a spring 48. 80 This spring is secured by a screw 49 to the bracket arm 45 and bears at its free end against the sliding latch. This latch is slotted at 50 to receive the stems of headed screws 51 which are received at their threaded ends in tapped openings in the bracket arm 45. The latch is thus supported and guided for sliding movement fore and aft of the machine and is provided with a finger piece 47^a by which it may be moved to the 85 releasing position. The forward movement of the latch is limited by a lug 52 against which the forward end of the latch is adapted to bear when the latch is moved to its normal position by the spring 48. Body 100 portions 53 and 54 of the latch are adapted to overlie the pins 43 when the latch is in its locking position, thus preventing a detachment of the supporting bar and holding it rigidly on the platen frame. The latch 105 is also provided with a cut-out 55 and a free end portion 56. When the latch is moved rearwardly by its finger piece 47^a to its releasing position, the cut-out or recess 55 in the latch is brought into register with 110 the rear pin 43, whereas the terminal portion 56 of the latch clears the forward pin 43. At this time the left-hand end of the supporting bar may be lifted out of its bearings 44 and a slight endwise movement of 115 the bar to the left at this time is effective to detach the bar, together with the parts carried thereby, from the machine for purposes which will hereinafter more clearly appear. This rigidly supported bar 38 is provided 120 with two surrounding sleeves 57, each carrying a set screw 58 threaded therethrough and adapted to bear at its inner end against the supporting bar to hold the associated sleeve in the position to which it may be adjusted along the supporting bar.

Pins 59 project upwardly from the supporting bar to co-act with the bearing sleeves 57 to limit the extent of outward adjustment of the latter. Each bearing sleeve 125 130

supports a rearwardly projecting rigid arm 60 provided at the rear end thereof with a card guide, designated as a whole by the reference numeral 61. This card guide is fixedly connected to its supporting arm and is provided with a flat guiding or bearing surface 62 against which the card or stencil sheet is adapted to bear. The outer edge of each guide is provided with a flange 63 which projects at right angles to the plane of the body or flat portion 62 of the guide to form a side edge guide for the card or stencil sheet. This side edge guide is curved at its edge, as indicated at 64, to conform substantially to the curvature of the platen, so that the side edge guide may be brought sufficiently close to the platen to coact efficiently with the stencil card or sheet when the latter is introduced into the machine between the card guides and the platen.

Each supporting arm 60 supports a carrier or slide 65 which is in the nature of a sleeve that is rectangular in cross section to conform to the shape of the supporting arm.

Each sleeve or slide is adapted to move on its supporting arm 60 fore and aft of the machine, and is provided with a depending bracket arm 66 which may be formed integral with the slide 65 and is apertured at 67 to receive a feed roller 68 in the apertured portion thereof. The lower ends of the bracket arms of each slide are turned at 69 to constitute a bearing for a supporting sprindle 70 for the associated feed roller 68.

From an inspection of Figs. 3 and 5 it will be understood that each card guide is apertured at 71 to enable the associated feed roller 68 to extend therethrough into contact with the card or stencil sheet located between the guides and the platen, and to bear against said card near the printing line and above the latter as indicated in Figs. 1 and 4. In Figs. 1 and 4, I have illustrated a stencil sheet or card of the usual construction in position in the machine to receive the first line of writing. This stencil card is designated as a whole by the reference numeral 72 and comprises a rectangular open card board frame 73, a reinforcing sheet 74 and a central stencil sheet 75. It will be understood from these figures that the feed rollers 68 bear against the stencil card at the side edge portions thereof above the printing line when the card is introduced between the guides and the platen. It will also be understood that the side edge guides 63 on the card guides coöperates with the side edges of the stencil card to direct the latter in its introduction into the machine and in the feed of the card in its line spacing movements, thus enabling the card to be properly introduced and squared in the machine and to be accurately fed in a substantially flat condition. It will also be observed from these figures that the relation of the card guides to the printing line is such that when a stencil card of the character shown is introduced into the machine and the top edge thereof is in register with the upper ends of the card guides, the stencil card will be in position to receive the first line of writing. While the card guides are open-ended, no support being provided for the lower ends of the stencil cards, nevertheless, they may be accurately positioned in the machine, the upper ends of the card guides constituting indicating means to facilitate a proper adjustment of the stencil card. Pressure is exerted upon the slide or carrier for each feed roller 68 by a coiled expansion spring 76 which bears at one end against the associated slide 65 and at its opposite end against the part 77 of the associated bearing sleeve 57. The force of each spring 76 therefore is exerted to move its slide 65 along the supporting arm or rod 60 and press the associated feed roller 68 against the platen or the card interposed between the platen and said feed roller.

I have provided means whereby both of the feed rollers 68 may be simultaneously released in order to properly introduce a card in position or to effect an adjustment thereof. In the present instance these releasing means comprise a rock shaft 78 arranged in front of the platen and supported to turn in bearings in bracket arms 79. These arms project from sleeves 80 which are angular in cross section and surround the rigidly supported bar 38. The supporting sleeves 80 are tapped to receive set screws 81 by which they may be secured to the supporting bar 38 in the positions to which they may be adjusted along the latter. The rock shaft 78 projects beyond its bearings and each end is provided with a finger piece 82 fixedly connected with the rock shaft and held in place by a screw 83. Each finger piece 82 is formed with a depending arm 84 (see Fig. 5) from which extends a laterally projecting pin 85. Each pin 85 is received in and extends freely through an opening in the forward end of a link 86. The rear end of each link is provided with a sleeve 87 which projects laterally therefrom and is received on a bearing pin 88, headed slightly at its end 89, to prevent the link from being displaced from its pin. Each pin 88 is carried by and projects from the associated slide 65 which carries one of the feed rollers 68. The pins 85 passing loosely through openings in the links 86 afford a relative adjustment between the supporting arms 60, and the card guides and feed rollers carried thereby, without a disconnection being effected between the pins 85 and the links 86. It follows therefore that whatever the relative adjustment between the arms 60 and the parts carried thereby may be, the finger pieces 82 are at 125

all times connected with the slides 65 and are effective to simultaneously release both of the feed rollers 68 carried by the slides. Thus, a depression of either finger piece 82 causes the shaft 78 to be turned, thereby producing a forward movement of both of the pins 85 and the links 86 controlled thereby. This is effective to move both of the slides 65 forwardly against the pressure of the springs 76, thereby releasing both feed rollers from the stencil card. The pins 59, hereinbefore referred to, prevent a relative outward adjustment between the supporting arm 60, and the parts carried thereby, to such an extent that the pins 85 can no longer co-act with the links 86 to effect a release of the feed rollers. This relative adjustment between the arms 60 is effective to bring about an adjustment of the card guides and feed rollers 68 longitudinally of the platen toward or away from each other, so as to accommodate the devices to cards of different widths. It will be understood that the movement of the feed rollers into and out of engagement with the card, through an actuation of the releasing means or otherwise, is effected independently of the card guides which are of rigid construction and are rigidly supported on the bar 38 in a position where they may at all times co-act with the cards irrespective of the positions of the feed rollers.

As shown, each card guide crosses the printing line so that each guiding surface 62 and side guide 63 extends above and below the printing line and is effective to receive the card when it is first introduced into the machine and accurately guide it to the feed rollers 68 and to the printing line, and assure an accurate positioning and feed of each card in the machine.

Should the devices carried by the supporting bar 38 interfere with the feed of the work sheet in the ordinary manner when the latter is introduced in the rear of the platen and bent around the same, the latch 47 may be moved to the releasing position and the supporting bar 38 and the parts carried thereby removed as an entirety from the machine. It is essential that at this time some means be employed to co-operate with the ordinary work sheet to hold it in position against the platen at the printing line and aid in the forward feed of the work sheet. Any suitable means may be employed for this purpose which will not interfere with the use of the stencil card feed devices. In the present instance I have employed a feed roller 90 which extends throughout, or substantially throughout, the length of the platen above the printing line. The spindle or shaft of the feed roller is reduced at its ends and is received in bearing openings in supporting arms 91 fixed at their lower ends to a rock shaft 92. It will

be seen from an inspection of Fig. 6 that this rock shaft is reduced at its ends, at 93, where it is received in shouldered bushings 94 which in turn are received in bearing openings in the end plates of the platen frame 11. These bearing openings are usually employed for another purpose which need not be described. The outer end portions of the rock shaft 92 are flattened on the sides thereof, as at 95, to fixedly connect 70 crank arms 96 thereto. Each crank arm has an opening, the contour of which corresponds to the cross section of the shaft at each end thereof. A headed screw 97 is received in a tapped opening at each end of 80 the shaft to hold the associated crank arm 96 on the shaft. Contractile springs 98 are connected at their upper ends to the crank arms 96 and at their lower ends to screws 99 which are received in tapped openings in 85 lugs 100 projecting from the end plates of the platen frame. A finger piece 101 is secured by screws 102 to the left-hand supporting arm 91 so as to provide convenient means for releasing the feed roller 90 from 90 co-operation with the platen or the paper thereon. It will be understood that the power of the springs 98 is exerted through the crank arms 96 and rock shaft 92 to press the feed roller 90 against the platen; but 95 that this pressure may be released at any time by a forward movement exerted on the finger piece 101. It will be understood that the position of the feed roller 90 is such that it does not interfere with the feed of the 100 card in a flat, or substantially flat, condition, said feed roller at this time remaining in the rear of the card and out of contact therewith, and so disposed that it will prevent an accidental backward bending of the card to 105 an extent which would injure it, as will be understood from an inspection of Fig. 1. The position of this feed roller, moreover, is such that it may be employed at any time with work sheets which are introduced in 110 the rear of the platen and brought around and fed over the platen in a curved condition, said feed roller maintaining the paper against the face of the platen so as to conform to the curvature thereof at and near 115 the printing line.

It is believed that the operation of the devices for writing stencil cards or the like will be understood from the foregoing description. The feed rollers 68 are first released through an actuation of one of the finger pieces 82 and the card is introduced between the card guides and the platen as indicated in Fig. 4, the top edge of the card registering with the upper ends of the card 120 guides. The finger piece 82 is then released and the feed rollers 68 will clamp the card in place. The card is then in position to receive the first line of writing, assuming that the carriage has been moved to the limit of 125 130

its movement to the right. After this first line is completed the line spacing handle 17 may be actuated in the usual manner to return the carriage to the beginning of a new line and to effect a line spacing movement of the platen, thereby effecting a feed of a card to begin writing the second line thereon. After this line is written the card is removed, assuming that but two lines are to be written thereon. The removal of the card may be effected by a forward feed of the platen produced by one of the finger wheels, thereby feeding the card upwardly out of the guides and removing it by hand. 10 Another card may be introduced in the manner previously described and the operation is continued indefinitely.

15 I use the term "card" herein in a broad sense to include index or blank cards, stencil sheets of the character shown, envelopes or any comparatively stiff work sheets as distinguished from comparatively thin flexible work sheets which may be readily bent around the platen without injury thereto.

20 25 What I claim as new and desire to secure by Letters Patent, is.—

1. In a front-strike typewriting machine, the combination of a carriage; a cylindrical platen carried thereby; and means for supporting, guiding and feeding cards substantially in a flat condition in front of said platen, said means comprising card guides having substantially flat guiding surfaces which cross the printing line and between 25 which and the platen the card may be introduced, said guides receiving their support in front of the platen, feed rollers which co-act with the platen near the printing line and which are adapted to engage the side edge portions of a card guided by said guides, and means for moving said feed rollers away from the platen independently of said guides and while the latter remain at rest and in coöperative relation with the 45 card.

2. In a front-strike typewriting machine, the combination of a carriage; a cylindrical platen carried thereby; and means for guiding cards substantially in a flat condition in 50 front of the platen, said means comprising card guides open or unobstructed at the upper and lower ends thereof and having substantially flat guiding surfaces which cross the printing line and between which and the platen a card may be introduced, each of the 55 guides also having a side edge guide at right angles to the body portion thereof, and which co-acts with a side edge of a card as the card is introduced into the machine and 60 before it reaches the printing line.

3. In a front-strike typewriting machine, the combination of a carriage; a cylindrical platen carried thereby; and means for supporting, guiding and feeding cards substantially in a flat condition in front of said 65

platen, said means comprising feed rollers which co-act with the platen near the printing line, and rigidly supported rigid card guides having substantially flat guiding surfaces which cross the printing line and between which and the platen a card may be introduced, each of said guides also having a side edge guide extending above the printing line and bent at right angles to the plane of the body portion of the guide to coöperate with a side edge of a card before the card reaches said feed rollers. 70

4. In a front-strike typewriting machine, the combination of a carriage; a cylindrical platen carried thereby; and means for guiding cards substantially in a flat condition in front of the platen, said means comprising card guides having substantially flat guiding surfaces which cross the printing line and between which and the platen a card 80 may be introduced, each of the guides also having a side edge guide at right angles to the body portion thereof and which extends above the printing line and co-acts with a side edge of a card before the card reaches 85 the printing line; said side edge guides having their edges curved to conform substantially to the curvature of the platen.

5. In a front-strike typewriting machine, the combination of a carriage; a cylindrical 90 platen carried thereby; and means for guiding cards substantially in a flat condition in front of the platen, said means comprising open ended card guides having substantially flat guiding surfaces which cross the printing line and between which and the platen a card 95 may be introduced, each of the guides also having a side edge guide at right angles to the body portion thereof and which crosses the printing line and co-acts with a side edge of a card, a supporting bar on the carriage and in front of the platen and by which said guides are supported in place, and means by which said bar with the 100 guides thereon may be readily detached 105 from the carriage.

6. In a front-strike typewriting machine, the combination of a carriage; a cylindrical platen carried thereby; and means for guiding cards substantially in a flat condition in 110 front of the platen, said means comprising open ended card guides having substantially flat guiding surfaces between which and the platen a card may be introduced, each of the 115 guides also having a side edge guide at right angles to the body portion thereof and which co-acts with a side edge of a card, the relation of the guides to the printing line being such that when the upper edge of a 120 card is in register with the tops of the guides 125 the card will be in position to receive the first line of writing near the top of the writing field of the card.

7. In a front-strike typewriting machine, the combination of a carriage; a cylindrical 130

- platen carried thereby; means for guiding cards substantially in a flat condition in front of the platen, said means comprising open ended card guides having substantially flat guiding surfaces between which and the platen a card may be introduced, each of the guides also having a side edge guide at right angles to the body portion thereof and which co-acts with a side edge of a card, the upper ends of the guides constituting indicating means which enables a card to be properly located with reference to the printing line and to bring the card into position to receive the first line of writing near the top of the writing field of the card; and feed rollers co-operative with the platen near the printing line and which are co-operative with the side edge portions of a card directed by the guides.
- 20 9. In a front-strike typewriting machine, the combination of a carriage; a cylindrical platen carried thereby; and means for guiding cards substantially in a flat condition in front of the platen, said means comprising open ended guides having substantially flat upright rigid guiding surfaces which cross the printing line and between which and the platen a card may be introduced, forwardly extending rigid arms which carry said guides, a rigidly mounted bar carried by the carriage in front of the platen and which carries said arms, and a latch for affording a detachment of said bar and the parts carried thereby.
- 35 9. In a front-strike typewriting machine, the combination of a carriage; a cylindrical platen carried thereby; means for guiding cards substantially in a flat condition in front of the platen, said means comprising open ended guides having substantially flat upright rigid guiding surfaces which cross the printing line and between which and the platen a card may be introduced, forwardly extending rigid arms which carry said guides, and a rigidly mounted bar carried by the carriage in front of the platen and which carries said arms; and spring pressed feed rollers which are movable independently of said guides and co-operate with the platen near the printing line and engage a card at the side edge portion thereof.
- 40 10. In a front-strike typewriting machine, the combination of a carriage; a cylindrical platen carried thereby; means for guiding cards substantially in a flat condition in front of the platen, said means comprising open ended guides having substantially flat upright rigid guiding surfaces which cross the printing line and between which and the platen a card may be introduced, forwardly extending rigid arms which carry said guides, and a rigidly mounted bar carried by the carriage in front of the platen and which carries said arms; and spring pressed feed rollers which are movable independently of said
- 45 50 55 60 65

guides and co-operate with the platen near the printing line and engage a card at the side edge portions thereof; and hand controlled means operable at will for simultaneously releasing said feed rollers.

11. In a front-strike typewriting machine, the combination of a carriage; a cylindrical platen carried thereby; means for guiding cards substantially in a flat condition in front of the platen, said means comprising open ended guides having substantially flat upright rigid guiding surfaces between which and the platen a card may be introduced, forwardly extending rigid arms which carry said guides, and a rigidly mounted bar carried by the carriage in front of the platen and which carries said arms; carriers that are mounted on said arms and adapted to slide thereon fore and aft of the machine; springs for forcing said carriers toward the platen; and feed rollers carried by said carriers.

12. In a front-strike typewriting machine, the combination of a carriage; a cylindrical platen carried thereby; means for guiding cards substantially in a flat condition in front of the platen, said means comprising open ended guides having substantially flat upright rigid guiding surfaces between which and the platen a card may be introduced, forwardly extending rigid arms which carry said guides, and a rigidly mounted bar carried by the carriage in front of the platen and which carries said arms; carriers that are mounted on said arms and adapted to slide thereon fore and aft of the machine; springs for forcing said carriers toward the platen; feed rollers carried by said carriers; and hand actuated means operable at will for simultaneously moving both of said carriers forward to release the feed rollers.

13. In a front-strike typewriting machine, the combination of a carriage; a cylindrical platen carried thereby; means for guiding cards substantially in a flat condition in front of the platen, said means comprising open ended guides having substantially flat upright rigid guiding surfaces between which and the platen a card may be introduced, forwardly extending rigid arms which carry said guides, and a rigidly mounted bar carried by the carriage in front of the platen and which carries said arms; carriers that are mounted on said arms and adapted to slide thereon fore and aft of the machine; springs for forcing said carriers toward the platen; feed rollers carried by said carriers; a rock shaft carried by said bar; a finger piece for rocking said shaft; and connections between said rock shaft and carriers for moving the latter forward and releasing the feed rollers.

14. In a front-strike typewriting machine, the combination of a carriage; a cylindrical

- 5 platen carried thereby; means for guiding cards substantially in a flat condition in front of the platen, said means comprising open ended guides having substantially flat upright rigid guiding surfaces between which and the platen a card may be introduced, forwardly extending rigid arms which carry said guides, and a rigidly mounted bar carried by the carriage in front of the platen and which carries said arms; carriers that are mounted on said arms and adapted to slide thereon fore and aft of the machine; springs for forcing said carriers toward the platen; feed rollers carried by 10 said carriers; a rock shaft carried by said bar; a finger piece for rocking said shaft; connections between said rock shaft and carriers for moving the latter forward and releasing the feed rollers; and means for affording a detachment of said bar together with the guides, feed rollers and rock shaft.
- 15 15. In a front-strike typewriting machine, the combination of a carriage; a cylindrical platen carried thereby; and means for guiding cards substantially in a flat condition in front of the platen, said means comprising open ended guides having substantially flat upright rigid guiding surfaces which cross the printing line and between which and the platen a card may be introduced, forwardly extending rigid arms which carry said guides, a rigidly mounted bar carried by the carriage in front of the platen and which carries said arms, and means for affording a relative adjustment between said arms in order to bring the guides nearer to or move them farther from one another and thus accommodate the guides to cards of different widths.
- 20 16. In a front-strike typewriting machine, the combination of a carriage, a platen carried thereby, a bar arranged in front of the platen, arms which extend fore and aft of the machine and which are carried by said bar, feed rollers carried by said arms and coöperative with the platen near the printing line, and hand actuated means for simultaneously releasing said feed rollers.
- 25 17. In a front-strike typewriting machine, the combination of a carriage, a platen carried thereby, a bar arranged in front of the platen, arms which extend fore and aft of the machine and which are carried by said bar, feed rollers carried by said arms and coöperative with the platen near the printing line, means for affording a relative adjustment between said feed rollers longitudinally of the platen, and hand actuated means for simultaneously releasing said feed
- 30 rollers.
- 35 18. In a front-strike typewriting machine, the combination of a carriage, a platen carried thereby, a bar arranged in front of the platen, feed rollers carried by said bar and coöperative with the platen near the print-
- 35 ing line, hand actuated means for simultaneously releasing said feed rollers, and hand actuated spring pressed means for affording a detachment of said bar together with the feed rollers and said releasing means.
- 40 19. In a front-strike typewriting machine, the combination of a carriage, a platen carried thereby, feed rollers arranged in front of the platen, a rock shaft carried by the carriage in front of said platen, a finger piece for turning said rock shaft, intermediate connections between said rock shaft and said feed rollers for simultaneously releasing them, a supporting bar in front of the platen and which carries said rock shaft and feed rollers, and hand actuated means for releasing said supporting bar and enabling it with the parts carried thereby to be removed from the machine.
- 45 20. In a front-strike typewriting machine, the combination of a carriage, a platen carried thereby, feed rollers arranged in front of the platen, means for affording a relative adjustment of said feed rollers longitudinally of the platen, a rock shaft in front of the platen, a finger piece for controlling said rock shaft, and links between said rock shaft and said feed rollers, whereby said finger piece is operative to simultaneously release said feed rollers irrespective of the relative adjustment between them.
- 50 21. In a front-strike typewriting machine, the combination of a carriage, a platen carried thereby, feed rollers arranged in front of the platen, means for affording a relative adjustment of said feed rollers longitudinally of the platen, a rock shaft in front of the platen, a finger piece for controlling said rock shaft, links between said rock shaft and said feed rollers, whereby said finger piece is operative to simultaneously release said feed rollers irrespective of the relative adjustment between them, a supporting bar which carries said rock shaft and feed rollers, and a hand actuated latch by which said supporting bar may be released and detached from the machine together with the parts carried thereby.
- 55 22. In a front-strike typewriting machine, the combination of a carriage, a platen carried thereby, rigidly supported arms which extend fore and aft of the machine in front of the platen, a spring-pressed slide carried by each of said arms, a feed device carried by each of said slides and coöperating with the platen at the front side thereof, and hand actuated means for simultaneously moving said slides forward to release said paper feed devices.
- 60 23. In a front-strike typewriting machine, the combination of a carriage, a platen carried thereby, rigidly supported arms which extend fore and aft of the machine in front of the platen, a guide carried by each of said

arms, a spring pressed slide on each of said arms and movable thereon independently of said guides, a feed roller carried by each slide, and hand actuated means for simultaneously moving the slides and releasing the feed rollers while the guides remain fixed.

24. In a front-strike typewriting machine, the combination of a carriage, a platen carried thereby, rigidly supported arms which extend fore and aft of the machine in front of the platen, a guide carried by each of said arms, a spring pressed slide on each of said arms and movable thereon independently of said guides, a feed roller carried by each slide, hand actuated means for simultaneously moving the slides and releasing the feed rollers while the guides remain fixed, a bar which carries said arms and said releasing means, and hand actuated means which afford a removal of the bar together with the releasing means, arms, guides and feed rollers.

25. In a front-strike typewriting machine, the combination of a carriage, a platen carried thereby, a bar carried by the carriage in front of the platen, arms carried by said bar and extending fore and aft of the machine, guides fixed to said arms, spring pressed slides which move fore and aft of the machine on said arms, feed rollers which are carried by said slides, a rock shaft carried by said bar, a finger piece for turning said rock shaft, and links between said rock shaft and slides for moving the slides forward when the shaft is turned by said finger piece.

26. In a front-strike typewriting machine, the combination of a carriage, a platen carried thereby, a bar carried by the carriage in front of the platen, arms carried by said bar and extending fore and aft of the machine, guides fixed to said arms, spring pressed slides which move fore and aft of the machine on said arms, feed rollers which are carried by said slides, a rock shaft carried by said bar, a finger piece for turning said rock shaft, links between said rock shaft and slides for moving the slides forward when the shaft is turned by said finger piece, and hand actuated means for releasing said bar and enabling it together with the parts carried thereby to be removed from the machine.

27. In a front-strike typewriting machine, the combination of a carriage, a platen carried thereby, a bar arranged in front of the platen, feed rollers carried by said bar and coöperative with the platen near the printing line, and an additional feed roller which extends throughout the length of the platen and is arranged above and in the rear of said first mentioned feed rollers.

28. In a front-strike typewriting machine,

the combination of a carriage, a platen carried thereby, a bar arranged in front of the platen, feed rollers carried by said bar and coöperative with the platen near the printing line, an additional feed roller which extends throughout the length of the platen and is arranged above and in the rear of said first mentioned feed rollers, and means independent of said bar for supporting said additional feed roller.

29. In a front-strike typewriting machine, the combination of a carriage, a platen carried thereby, a bar arranged in front of the platen, feed rollers carried by said bar and coöperative with the platen near the printing line, hand actuated means for simultaneously releasing said feed rollers, an additional feed roller which extends throughout the length of the platen and is arranged above and in the rear of said first mentioned feed rollers, and independent means for releasing said additional feed roller.

30. In a front-strike typewriting machine, the combination of a carriage, a platen carried thereby, a bar arranged in front of the platen, feed rollers carried by said bar and coöperative with the platen near the printing line, hand actuated means for simultaneously releasing said feed rollers, hand actuated means for affording a detachment of said bar together with the feed rollers and said releasing means, an additional feed roller which extends throughout the length of the platen above and in the rear of said first mentioned feed rollers and which is supported independently of said bar, and independent means for releasing said additional feed roller.

31. In a front-strike typewriting machine, the combination of a carriage, a platen carried thereby, a bar arranged in front of the platen, feed rollers carried by said bar and coöperative with the platen near the printing line, means for affording a relative adjustment between said feed rollers longitudinally of the platen, hand actuated means for simultaneously releasing said feed rollers, hand actuated means for affording a detachment of said bar together with the feed rollers and said releasing means, an additional feed roller which extends through the length of the platen above and in the rear of said first mentioned feed rollers and which is supported independently of said bar, and independent means for releasing said additional feed roller.

Signed at London, England, this seventeenth day of June, A. D. 1915.
